UNITED STATES PATENT OFFICE.

JAKOB LICHTENBERG, OF BERGISCH-GLADBACH, GERMANY.

SAFETY DEVICE FOR MINE CAGES.

Application filed August 5, 1925. Serial No. 48,351.

This invention relates to an improved safety-device for mine cages, of the type in which by means of a spring-pressed friction-roller screw-spindles having right-and left-hand screw-threads are operated for pressing the braking-jaws upon the guide-beams.

The novelty of the improvement consists in the fact that the friction-roller with stretched suspension-rope of the cage is held in its lifted position by means of turnable claws engaging below the fork of the friction-roller and which are adjusted in horizontal position by erection of their angle-levers connected with said rope, while with unstretched or torn rope they are turned-over and thus liberate said fork which is acted-upon by a spring. Said fork acts upon locking pawls connected therewith by links and which engage with the toothings of fixed brackets on the cage.

By supporting the fork connecting the friction-roller with the operating spring, by means of said claws of which the position depends upon the stretching condition of the rope of the cage, the effect—already known in connection with similar safety-devices but obtained by different means—is attained that the friction-roller is prevented from being brought into its operative position by the normal rope vibrations only.

By means of the locking-pawls engaging with said toothings, it is attained that the friction-roller, upon being brought in contact with its guiding-race, is locked in this position.

The invention consists in attaining said two effects at a time by the fork connecting the friction-roller with the operating spring being locked by means of said angle-levers connected with the rope of the mine cage and allowing, at its movement following the disengagement of said locking action, pawls to engage in fixed toothings which prevent the friction-roller returning from its engaged position.

The accompanying drawing illustrates the improved arrangement: Fig. 1 is a sectional side view, on the line A—B of Fig. 4, of the improved safety-device in its inoperative position, Fig. 2 is a similar view to the former showing the safety-device in its operative position, and Figs. 3 and 4 are respectively a front view and a plan view of the improved arrangement.

The friction-roller 1 turns on a shaft 2

mounted in two supports 3 which are turnably arranged on a cylindrical nut 4. The latter, when turned, moves two right-and left-hand screw-spindles 5, 6 for pressing the breaking-jaws 7 against the guide-beams 60. The driving of the nut 4 is effected by means of a spur-wheel 9 keyed on the nut 4 and in gear with a toothed-wheel 10 integral with the friction-roller 1. The latter is acted upon by a pressure-spring 11 with 65 which it is connected by means of the fork 12 attached to the shaft 2.

With stretched rope 18, the friction-roller 1 is in its lifted position in which it is locked by means of claws 14 turnable in brackets 79 13 and engaging below catches 15 of the fork 12. The angle-levers 14^a rigidly connected with the claws 14 at about a right angle are in connection with the cage rope 18 by means of chains 16 attached to a common strap 17 fixed to the rope 18. With stretched rope, thus, the claws 14 are held in horizontal position. With vibrations in the stretching of the rope not exceeding a certain normal limit, thus, the friction-roller 80 1 is held out of engagement with the guiding-race 19 as is known in the art.

With unstretched or torn rope 18, however, the supports for the fork 12 are done away by the claws 14 being free to turn-over. Consequently, the fork 12 is pulled down by action of the spring 11 until the friction-roller 1 makes contact with its guiding-race 19. Said contact is maintained in a way known in the art by the friction-roller 1 being locked in its lowered position by means of pawls 20 pivoted at one end to the supports 3 and connected at the other end by links 21 with the fork 12. Said pawls engage by action of the spring 95 11 in the toothings 22^a of fixed brackets 22 on the cage and prevent the friction-roller 1 returning to its inoperative position, said roller being then turned by its contact with the guiding-race 19 and thus turning the nut 100 4 for operating the braking-jaws 7.

What I claim, is:

In combination, a mine cage, breaking-jaws thereon, a driving friction-roller normally held in its inoperative position, a screw-gearing adapted to operate said breaking-jaws upon disengagement of said friction-roller from its inoperative position, a spring-pressed fork attached to the shaft of said roller and adapted to hold the latter 110

in its inoperative as well as in its operative positions; catches on said fork, a suspension-rope for the mine cage, turnable claws engaging with said catches with stretched rope to which said claws are attached, and locking-pawls adapted to be operated with unstretched or torn rope and to lock said fric-

tion-roller in its operative position, substantially as set forth.

In testimony whereof I have hereunto set ¹⁰ my hand in the presence of two subscribing witnesses:

JAKOB LICHTENBERG.
